UNITED STATES PATENT OFFICE.

HARLEY R. PHILLIPS, OF OAK PARK, ILLINOIS, ASSIGNOR TO MOJONNIER BROS. CO.
A CORPORATION OF ILLINOIS.

CONTAINER-FORMING MACHINE.

Application filed March 29, 1924. Serial No. 702,814.

To all whom it may concern:

Be it known that I, HARLEY R. PHILLIPS, a citizen of the United States, residing at Oak Park, in the county of Cook and State of Illinois, have invented certain new and useful Improvements in Container-Forming Machines, of which the following is a specification.

The present invention relates generally to container forming machines and has to do more particularly with machines for making containers out of flexible sheet material, such as pasteboard, paper and the like.

In the manufacture of containers for holding ice cream, it is common to employ an outer container or carton of substantial material so that it will not collapse in service, and then line the same with a container of lighter material, such as parchment paper, which will be impervious to the contents. The inner container when so used is commonly called a "liner."

Although my invention is capable of general use in the forming of containers, I have disclosed it herein as applied to the making of these liners.

One object of the invention is to construct a machine of the class mentioned which will produce a container of simple construction having smooth interior walls so that when used for holding ice cream a neat brick will be produced. Another object is to produce a machine which will leave but a few hand operations to be performed during the making of the container. By having a few hand operations the machine is materially simplified in construction. Another object is to produce a machine which is durable and capable of efficient operation by unskilled labor.

In devising a machine to meet these objects, I preferably employ a forming block and a cooperating channel into which the block may be moved to shape the blank about the block to form three sides of the container. Treadle operated folding plates then come into play successively to fold the blank at the end of the block to form the bottom of the container. A few hand operations complete the formation of the remaining side of the container and put the same in readiness to receive the carton. This is slipped over the lining container while on the block. A sleeve on the block is then moved to turn the flaps upon the

liner and carton back upon the latter. The lined carton is then withdrawn by hand from the block.

The various features of the invention include the block and channel, a clamp associated with the block and adapted to engage the blank as the block enters the channel, the novel folding plates for forming the bottom of the container, the means for operating these plates in proper sequence, the mounting of the block and its actuating means, the sleeve upon the block for turning back the container and carton flaps, the specific mounting of the folding plates upon axes in the same plane, and other features which will more fully appear upon consideration of the following detailed description taken in connection with the accompanying drawings, the scope of the invention being particularly pointed out in the appended claims.

In said drawings, Fig. 1 is a plan view of a container forming machine constructed in accordance with the present invention; Fig. 2 is a vertical elevation of the same, parts being shown in section taken on a plane indicated by the line 2-2 of Fig. 1; Fig. 3 is a vertical section through the channel, the block, the clamping tongue and the adjacent parts of the machine, the plane of section being indicated by the line 3-3 of Fig. 1; Fig. 4 is a horizontal section illustrating particularly the means for operating the folding plates, the plane of section being indicated by the line 4-4 of Fig. 2; Fig. 5 is a perspective view of a portion of the machine illustrating the forming block above the channel with a container blank upon the table as the parts appear at the beginning of operations; Fig. 6 is a similar view illustrating the positions of the machine parts and the blank after the block has passed down into the channel and the primary folding plate has been moved to its closed position; Fig. 7 is a similar view illustrating the positions of the machine parts and the blank after the secondary folding plate has been moved to its closed position; Fig. 8 is a similar view illustrating the parts and blank after the tertiary folding plate has been moved to its closed position; Fig. 9 illustrates the machine parts in the same position as Fig. 8, but shows the blank folded down upon the upper side of the block so as to form the

- fourth side of the container; Fig. 10 is a similar view showing the block raised up out of the channel and the surplus folds at the bottom of the container folded against its upper side wall ready to receive the carton; Fig. 11 is a perspective view of the block with the carton slipped over the lining container while the latter remains upon the block; Fig. 12 is a view similar to Fig. 10 showing the sleeve pushed forward upon the block so as to press the flaps of the liner and carton backward against the sides of the latter; Fig. 13 is an elevation of a portion of the front of the machine illustrating particularly the folding plates and their mountings; Fig. 14 is a vertical section of the same, taken on a plane indicated by the line 14—14 of Fig. 13; and Fig. 15 is a horizontal section of the same, taken on a plane indicated by the line 15—15 of Fig. 14. Throughout these views like characters refer to like parts.
- Referring to the drawings in detail, 20 designates the top of the table upon which 25 the various parts of the machine are mounted. The table structure includes the legs 21, 22, 23, 24, the side members 25, 26, the end members 27, 28, and a depending member 29. The legs and the depending member 30 may be variously connected by braces and cross bars, such as 30, to give the frame of the machine firmness and rigidity and to provide for the connection of the various parts. The table top is provided with a 35 central opening 32 which extends well toward the front of the table and provides space for the location and operation of the forming block 33. The rear of the table is provided with leaves 34 and 35 which are 40 secured to the table by hinges 36 and 37 and are adapted to be held in open position by pivoted retaining bars 38 and 39, of well known construction. These leaves extend the table top 20 and thus provide additional storage space for the accommodation 45 of the blanks from which the containers are to be manufactured. Obviously, the table and its parts may be composed of any suitable material, although wood in most instances would be preferable.
- The forming block 33 is a composite elongated member which protrudes from the rear of the machine toward the forward edge of the table. It is preferably constructed by joining four wooden strips, as 50 clearly illustrated in Figs. 3 and 5, so as to leave an opening 40 extending through its center. The forward end of the member 33 is given the shape which the container is to have. In the present embodiment I have 55 provided for a rectangular container, and therefore the end of the member 33 is rectangular. The member 33 is pivoted at a point adjacent to the rear edge of the table. 60 For this purpose it is provided with trun-
- nions 41 and 42 which project from its opposite sides and pass through bearing openings in angle plates 43 and 44, respectively. The latter have their horizontal webs secured to the table top 20 by any suitable 70 means, as the screws 45 and 46. The trunnions 41 and 42 are formed with bases 47 and 48, respectively, which are provided with screw holes so that they may be readily attached to the sides of the member 33 by 75 wood screws, such as 48^a. A bar 49 is secured at its forward end to the member 33 toward the rear end of the latter by any suitable means, as the screws 50, and extends rearwardly for a short distance where 80 it is connected to the upper end of the actuating rod 51 which passes through a hole in the end of the strip 49 and is provided with a nut 52 at its upper end. The lower end of the rod 51 is provided with an eye 85 51^a. A pin 53 passing through the eye 51^a pivotally secures the lower end of the rod 51 to the rear end of a treadle 54 which is provided with a step 55 at its forward end 90 and is pivotally secured by a bolt 56 at an intermediate point to the bracket 57 which in turn is mounted upon the depending member 29 at its lower end. The upper end of the rod 51 passes freely through the opening in the bar 49 so that when the operator presses his foot upon the step 55 and thus forces the rod 51 upward, it readily passes through the hole in the bar 49 and allows the forming block 33 to move downward under the action of gravity. As 95 clearly illustrated, the block 33 is so located that when it moves to its lowermost position its lower surface is substantially at the level of the upper face of the top 20. When the operator removes his foot from the step 100 55, the treadle 54 and the connected parts are restored to normal position by a coiled tension spring 58 which is secured at its lower end to the treadle 54 and at its upper end to the table member 26. The action of 105 this spring in drawing upward upon the forward end of the treadle 54 necessarily pulls upon the rod 54 so as to raise the forward end of the forming member 33 into 110 its uppermost position.
- The member 33, as previously stated, 115 operates with a channel located directly beneath it. This channel is formed by a channel member 59. As illustrated clearly in Fig. 3, the depressed portion of the member 59 which forms the bottom of the channel is secured to the table top 20 in any suitable way, as by the screws 60. At the upper limits of the portions of the channel member 59, which form the side walls of 120 the channels, the channel member extends laterally and at or near its outer edges rests upon brackets 61 and 62 and is secured to these brackets by any suitable means, as the screws 63 and 64 respectively. 125
- 130

The brackets 61 and 62 are higher at the forward edge of the table than they are toward the rear and, consequently, the flat upper faces of the channel member 59 are inclined downwardly and rearwardly. Gauge plates 65 and 66 are located upon the laterally extending portions of the channel member 59, and upon these gauge plates is placed the blank out of which the container is to be made. The laterally extending portions of the channel member 59 are apertured for the reception of pins 67 and 68 extending downward from the gauge plates 65 and 66 respectively. Sleeves 69 and 70 are secured to the channel member 59 beneath the apertures therein and serve to provide a substantial bearing for the pins 67 and 68. The gauge members 65 and 66 are provided with downwardly projecting portions which pass into the channel and form its side walls. When the gauge plates are in position, the forming block 33 fits between their depending portions which form the channel walls, with that degree of precision which will allow for the thickness of the blank and permit the latter to be readily shaped when forced downward into the channel by the member 33. To provide a smooth finish, the forward and rear portions of the laterally extending wings of the channel member 59 are provided with downwardly extending peripheral flanges, such as 71 and 72. The gauge plates are provided at their rear edges with gauges 73 and 74 which are secured in place by threaded bolts and thumb nuts 75 and 76. Each gauge 73 and 74 is provided with an upright flange and a lateral flange. The latter is in each instance provided with slots and the adjusting bolts pass through these slots to secure the gauges in proper position, and a lateral gauge 77 of like construction is positioned to the left of the gauge plate 65 and is similarly provided with slots and held in place by adjusting bolts and thumb nuts 78. The upright flanges of the gauges 73, 74 and 77 determine the position of the blank which rests upon the flat faces of the gauge plates 65 and 66 and extend over the channel 79 formed by the channel member 59, all as clearly illustrated in Fig. 5, where the blank 80 is in position to be operated upon by the descending forming block 33. As auxiliary to the gauge plates 65 and 66, I provide at the right of the plate 66 a tray 81 which rests upon the inclined bracket 62 and a similar inclined bracket 82. This tray is secured to these brackets in any suitable way, as by the screws 64 and 84. The rear edge of the tray 81 has an upturned flange 85. This tray is provided for the purpose of holding a pile of the blanks which are to be used in the making of containers. The downward and rearward inclination of the tray 81 is the same as that

of the plates 65 and 66. When desired, the gauge plates 65 and 66 may be replaced by other gauge plates having dimensions suited to blanks of a different size. When this is done it is not necessary to change the tray 81, as the blanks must be picked up individually by the operator in shifting them from the tray to their position upon the gauge plates 65 and 66. As illustrated in Fig. 3, the tray 81 slightly overlaps the channel member 59 at the point where the two are secured to the inclined bracket 62.

If we assume that a blank 80 is located upon the gauge plates 65 and 66, as indicated in Fig. 5, then it will be clear that if the operator steps upon the treadle 54, the forming block 33 will descend upon the blank and pass down into the channel 79 and carry with it the blank 80 so as to bring the latter with its edges upstanding, as indicated in Fig. 6. This action of the forming member and channel upon the blank obviously forms three sides of the container.

The bottom of the container is formed by the three folding members 86, 87 and 88. These are located at the forward end of the channel 79, being pivoted in the brackets 89 and 90. These brackets are respectively secured to the vertical channel walls of the channel member 59, preferably by screw bolts and co-operating nuts 91 and 92. The primary folding member 86 is provided at its lower edge with trunnions 93 and 94 which extend into openings in the brackets 89 and 90 respectively, said openings serving as bearings for the trunnions. It will be noted that the axis of rotation of the plate 86 is practically coincident with the line of intersection of the bottom of the channel with a vertical plane perpendicular to the channel walls. The plate 86 is positioned so that it will properly cooperate with the end of the forming block 33 in pressing the adjacent portion of the blank thereagainst. When this action takes place, the blank assumes the position indicated in Fig. 6. It will be noted that the plate 86 approximates the end of the block 33 in shape and area. For the purpose of operating the plate 86, it is provided with a crank arm 95 to which is connected the forward end of a connecting rod 96. This rod extends rearwardly through an opening 96a in the frame member 26 and at its rear end passes freely through an opening in a reciprocating head 97 carried at the upper end of a bar 98 which is pivotally mounted at its lower end upon the bolt 56 secured to the bracket 57. To secure unitary action between the bar 98 and the treadle 54, these parts are connected by a bar 99 which is secured at its opposite ends to said treadle and bar, respectively. It will be seen that when the operator presses upon the step 55 of the treadle 54, the head 97 at the upper end of the bar 98 will be moved

forward along the rod 96. This forward movement will initially produce no effect upon the rod 96. As the head advances, however, it engages a washer 100 at the rear end of a coiled spring 101 and compresses the latter against a collar 102 adjustably fixed to the rod 96. When this pressure becomes sufficient to overcome the resistance of the rod 96 and its connections, 10 said rod will be moved forward and the primary folding plate will be rocked from its open to its closed position to bring about the folding operation indicated in Fig. 6. When the pressure is removed from the 15 treadle 54, then the head 97 will be restored to its rear position through the agency of the tension spring 58 acting upon the treadle. This movement of the head will relieve the pressure on the spring 101 and allow 20 the folding plate 86 and its connections to be restored to normal position under the action of gravity.

The secondary folding plate 87 is provided with a downwardly projecting stem 103 which is provided with an apertured boss 104 at its lower end through which a vertical pivot pin 105 passes. A set screw 106 passing through the boss 104 firmly secures the folding plate to the pivot pin. 25 The latter extends through openings in the bracket 89 which serve as bearings for it. It will be noted that the axis of the pivot pin 105 is coincident with the inner edge of the folding plate 87 which is practically coincident with the line of intersection of the adjacent channel wall with the transverse vertical plane which includes the axis of the trunnions 93 and 94 30 of the folding plate 86. The secondary plate 87 is normally held in its open position by the action of a coiled spring 107 which passes at its lower end through an aperture in the lower end of the pin 105 and at its upper end is secured to the bracket 89 by a screw 108. It 35 will be seen that when the set screw 106 is loose, the pin 105 may be turned to tighten the spring 107 and thus provide any desired tension. When the pin 105 is thus adjusted, the set screw 106 may be screwed down, and 40 then the spring will normally hold the stem 103 of the plate 87 against a fixed portion of the structure in open position. In order to move the plate 87 to its closed position, it is provided with a crank arm 109 which 45 is connected at its outer end to the forward end of a connecting rod 110. This rod, like the rod 96, extends rearwardly through opening 96^a and at its rear end through an opening in the head 97 and is provided with 50 an adjustable collar 111, a coiled spring 112 and a washer 113, similar to the corresponding parts upon the rod 96. In this instance, however, the spring is shorter and, consequently, the head 97 does not by pressure 55 upon the washer 113 compress the spring 112 sufficiently to actuate the rod 110 until after the primary closing plate 86 has completed its closing movement. Then the rod 110 is pressed forward and rocks the plate 87 to its closed position. The effect upon the 60 blank 80 is to fold a portion of it against the plate 86 and bring the blank into the position illustrated in Fig. 7. Upon the return of the head 97 to its initial position under the action of the retractile spring 58, 65 the plate 87 is moved to its open position through the instrumentality of its return spring 107. As clearly shown, the outline of the plate 87 is triangular.

The structure and mounting of the tertiary folding plate 88 are similar to the structure and mounting of the secondary plate 87. The plate 88 has a stem 114 which terminates at its lower end in a boss 115 through which the pivot pin 116 passes. 70 The latter pin is, in this instance, journaled in bearings in the bracket 90 and is provided with a return spring 117 which is secured to the pin at its lower end by passing through a hole therein, and to the bracket 90 at its upper end by means of a screw 118. In this instance, the pin is secured to the boss 115 by a set screw 119, similar to the set screw 106, associated with plate 87. The axis of the vertical pin 116 is coincident with the inner edge of the plate 88, and the latter is practically at the line of intersection of the adjacent channel wall with the transverse vertical plane which 75 includes the axis of the trunnions 93 and 94 100 of the folding plate 86. Thus we see that the three folding plates have axes of rotation which lie in the same vertical plane, and that that plane is perpendicular to the walls and bottom of the channel. It will 105 also be noted that this plane is parallel to and closely adjacent to the plane of the end of the block 33, when the latter is in its lowermost position in the channel 79. In this instance, the spring 117 normally holds 110 the plate 88 in open position. It is moved to its closed position through the agency of a crank arm 120 connected at its outer end to the forward end of a connecting rod 121, which extends through the opening 96^a, and 115 at its rear end through an opening in the actuating head 97, similarly to the rods 96 and 110. The rod 121 is likewise provided with an adjustable collar 122, a coiled spring 123 and a washer 124, similarly arranged to the corresponding parts upon the associated rods. In this instance, the spring 123 is shorter than the spring 112 and the cross head does not, through the washer 124, 120 compress the spring 123 with sufficient force 125 to move the rod 121 until after the secondary folding plate 87 has been moved to its closed position. The effect of the closing movement of the plate 88 upon the blank 80 is to fold another portion of it to com- 130

plete the bottom of the container, as clearly illustrated in Fig. 8. The return of the head 97, as before, ultimately frees the rod 121 and allows the return spring 117 to bring 5 the folding plate 88 to its normal position.

The rear ends of the rods 96, 110 and 121 are provided with collars 125, 126 and 127, so that the rods cannot be slipped through the openings in the head 97 either by reason 10 of the quick return of the head to its normal position, or by the manipulation of the plates by hand without moving the head 97 forward. The collar upon the rod 96 also limits the return movement of the head 97 15 and thereby determines the return movement of the treadle 54. The collar 125 is almost in contact with the forward edge of the frame member 29 when the head 97 is in its normal position and, consequently, any blow 20 delivered by the head upon its return would be taken up by the collar 125 and the member 29 against which it would strike. It will also be noted that the downward movement of the step 55 upon the treadle 54 25 both releases the forming block to allow it to descend and moves the actuating head 97 forward. The springs 101, 112 and 123 are located upon the corresponding connecting rods so that the forming block will 30 reach the bottom of the channel before or at about the time the primary folding plate 86 begins to move. Then, as previously noted, the plate 86 completes its movement before the plate 87 begins to move and the latter 35 completes its movement before the plate 88 begins to move. Obviously, the springs 101, 112 and 123 may be variously positioned upon their rods by adjusting the collars 102, 111 and 122, by means of the set screws 40 shown therein. It will be apparent also that these springs might be more nearly equal in length and yet operate satisfactorily by shifting the positions of the collars.

When the blank and the parts of the machine are in the position of Fig. 8, the operator must perform a few hand operations to complete the forming of the carton. These consist in first turning the left hand portion of the blank, as viewed in Fig. 8, 45 down upon the top of the forming block 33. Following this, the right hand portion of the blank is turned down upon the block so as to overlap the portion turned in from the left. The upwardly extending portions 50 of the blank left by this operation are clearly indicated in Fig. 9. These must then be flattened down so as to occupy the position shown in Fig. 10. This completes the formation of the container and it is ready to receive the enclosing carton 128, shown in Fig. 11.

In order to firmly grasp the blank 80 at the time the forming block 33 descends upon it, I employ a clamping plate or tongue 129 55 which is secured at its rear end by a hinge

130 to the under side of the member 33. The forward end of the tongue 129 is provided with a flat portion in the form of a plate 131 which is of practically the same width as the block 33 and extends to a point adjacent to 70 its foremost end. The tongue 129 is apertured at a point adjacent to the hinge 130 and a bolt 132 passes through the aperture into the block 33. A coiled spring 133 on the under side of the tongue bears between 75 the same and the head of the bolt 132 and tends to force the tongue toward the block 33. The plate 131 of the tongue is held normally at the level of the gauge plates 65 and 66 in position to engage the under side of 80 the blank. This position is normally maintained by a flexible connection, such as the chain 134, which is secured at one end to the tongue 129, and at the other end to some portion of the frame structure. This might 85 be a fixed point but, in the present instance, I have shown it attached to the treadle 54 at a point where the latter does not have much movement. In operation, as the block 33 moves downward the forward end of the 90 tongue will also move downward by reason of the movement of the treadle 54, but such movement is very slight and does not interfere with the tongue plate 131 firmly pressing the blank against the under side of the 95 block 33 as soon as the latter has entered a little into the channel 79. Of course, if the lower end of the chain 134 be attached to an immovable point of the frame, then the 100 clamping action would take place just as soon as the block 33 in its descent reached the blank. Upon the return of the block 33 to its normal position, the plate is freed from the adjacent side of the formed container as soon as it reaches its normal position, since the chain 134 will then become 105 taut.

As soon as the container has been formed by the manual operations previously mentioned, the treadle may be allowed to return to 110 its normal position and the forming block 33 will then rise so as to bring the parts into the position of Fig. 10. Because of the way in which the folding plates 86, 87 and 88 have formed the folds at the bottom of 115 the carton, these folds readily slip off of the plates as the block 33 carries the liner upward. When the member 33 with the lining container upon it has been raised, then the carton 128 may be slipped on to the liner 120 by hand, as shown in Fig. 11. It then remains to turn the flaps of the liner and carton back upon the carton, as indicated in Fig. 12. This is accomplished by a sleeve 125 135 located upon the block 33 and adapted to be moved forward to the position of Fig. 12 to bring about this backward turn of the flaps. The sleeve 135 is slotted at its corners, as clearly illustrated, to provide four spring 130 tongues. The forward ends of these are

turned outward slightly so as to properly engage the flaps. The spring action of the tongues enables them to slip over the parts of the container and its liner without injuring them and yet with sufficient force to properly press them against the carton. The sleeve 135 is connected to the forward end of a bar 136 by means of a transverse pin 137. The latter passes through slots 138 in opposite sides of the forming member 33 and is held in position by cotter pins 139. The bar 136 engages the pin 137 within the interior chamber 40 of the member 33 and extends out through the rear end of said member and is there provided with a plurality of holes 140 by which it may be connected to the upper end of a lever 141 which, in turn, is connected to the bracket 57 by a pivot bolt 142 and extends forward terminating in a step 143. The upper end of the lever 141 is provided with a slot 144, and a transverse pin or bolt 145 passes through the slot 144 and one of the holes 140 in the rod 136. By this means a pin and slot connection is provided, and whenever the lever 141 is rocked from its normal position the rod 136 is thrust forward and the sleeve 135 is correspondingly moved. The plurality of holes 140 is provided so that the sleeve 135 may be set at different normal positions depending upon the length of the blanks used in the manufacture of the containers. Thus where containers of a sufficient size to hold a quart of ice cream are to be made, the container must be longer than where the container is to hold but a pint. In such cases, the containers have the same cross section, but the capacity is changed merely by varying the length. As illustrated in the drawing, the forward hole 140 is used, and therefore the sleeve 135 is positioned for use upon the larger size containers. In this connection it should be noted that the gauge plates 65 and 66 employed for long containers 45 would be replaced by similar gauge plates having their gauges 73 and 74 a shorter distance from the front than in the case of the plates illustrated. It will also be noted that in the normal position of the sleeve 135, the ends of the blanks 80 overlap the forward ends of the sleeve for a short distance. It will also be seen that the blank 80 has its rearward end slitted to form a plurality of flaps, a flap for each side of the container 50 except the fourth side where two overlapping flaps are necessary.

The lever 141 is restored to its normal position by a retractile spring 146 which is connected at its lower end to the lever 141 and at its upper end to a fixed portion of the frame, as the front member 26. The to and fro movement of the lever 141 is limited by a pin and slot connection with a bar 147 secured to the depending member 29 of the frame of the machine. The outer end

of the bar is provided with a slot 148, and a pin 149 upon the lever 141 passes through the slot 148. When the sleeve 131 is in its normal position, the pin 149 engages the outer end of the slot 148. When the lever 141 is actuated by the operator pressing upon the step 143, then the forward movement of the sleeve 135 is limited by the pin 149 engaging the forward end of the slot 148.

It will be understood that in carrying out my invention, many illustrations and modifications of the structure herein disclosed may be made without departing from the scope of the invention. I therefore do not wish to be limited to the specific matter disclosed, but aim to cover all such illustrations and modifications by the terms of the appended claims.

What I claim as new and desire to secure by Letters Patent is:

1. A machine for forming a rectangular container out of a blank of flexible sheet material, comprising a table having vertical channel walls, a forming block pivotally mounted upon the table and extending forward normally above and in line with the channel between said walls, a yielding clamping tongue pivoted to said block and cooperating therewith to clamp a blank thereagainst as the block is moved toward the channel, means whereby the blank may be positioned between said block and channel while the former is in normal position, and means for effecting a downward movement of the forward end of said forming block to press the blank against the tongue to clamp the blank and then move the tongue and blank down between said channel walls to cause the latter to press the blank against said form and thereby shape three sides of the container.

2. A machine for forming a rectangular container out of a blank of flexible sheet material, comprising a table having vertical channel walls, a forming block pivotally mounted upon the table and extending forward normally above and in line with the channel between said walls, a yielding clamping tongue extending beneath the form and mounted to cooperate with the latter in a blank-clamping action, means whereby the blank may be positioned between the block and tongue, primary, secondary and tertiary folding plates at the ends of said channel walls for folding portions of the blank against the end of the block to shape the end of the container, means for effecting a downward movement of said forming block to engage the blank and press it against the clamping tongue and then move the tongue and blank on down between the channel walls to cause the latter to press the blank against the block to form sides of the container, and means responsive to the operation of the aforesaid effecting means to suc-

cessively operate said primary, secondary and tertiary folding plates to shape the end of the container.

3. A machine for forming a rectangular lining container out of a blank of flexible material, comprising a protruding rectangular forming block, means whereby the blank may be readily folded about sides of the block and its exposed end to form sides and bottom of the container, the portion of the blank farthest from said end being slitted to form closing flaps for the top of the container, and means movable along said block to bend said flaps and the corresponding flaps of a carton slipped over said container while on said block, back against the sides of the carton.

4. In a container forming machine, a protruding rectangular forming block upon which a lining container and surrounding carton may be located with end flaps extending away from the end of the block and in position to overlap each other, and means movable lengthwise of said block to force said lining container flaps against said carton flaps and to bend the composite flaps back upon the sides of the carton.

5. In a container forming machine, a table having a channel in its top opening upward, a clamping tongue projecting into said channel and spring pressed upward, a rectangular forming block normally at rest above said channel and tongue, means for holding said tongue normally at the elevation of the upper edge of said table, and means for moving said block downward into said channel carrying said tongue with it and upward out of said channel and away from said tongue when the latter reaches its normal position.

6. In a container forming machine, a table having a channel in its top opening upward, a protruding rectangular forming block pivoted at the rear of the table and having its forward end normally at rest above said channel, a clamping tongue secured to the under side of said block and spring pressed upward toward the same, means for holding said tongue normally at the level of the table top away from said block, and means for rocking said block about its pivot to move its free end downward into said channel carrying said tongue with it and upward out of said channel and freeing itself from said tongue at the level of the table top.

7. A machine for forming a rectangular container out of a blank of flexible sheet material, comprising a rectangular forming block about which the blank is to be folded to form the container, means whereby the blank may be folded about sides of the block to form container sides, a primary bottom forming plate substantially coextensive in area with the end of said block

and pivoted at one edge near the edge of the block end and operative to fold the center of the adjacent end of the blank against said block end, a secondary bottom forming plate of triangular outline pivoted at one edge near another edge of said block end and operative to press a fold of the blank against said primary plate, and a tertiary bottom forming plate of triangular outline pivoted at its edge near a third edge of said block end and operative to press another fold of the blank against said primary plate, and means for operating said primary, secondary and tertiary plates in the order named.

8. A container forming machine including a table having vertical channel walls, a rectangular forming block normally at rest in line with and above the channel between said walls, a clamping member beneath said block operative to clamp a blank against the block as the latter is moved toward the channel, means whereby the blank may be positioned between said block and channel while the former is in normal position, a plurality of folding members at the end of said channel, means for moving said block down to first clamp the sheet and then carry it between said channel walls to fold the blank about said block to form container walls, means responsive to said moving means to operate said folding members to form the end of the container, and means for restoring said block with the container thereon to its normal position, said block in said latter position extending upward from the table at an angle for the ready manual slipping of a carton over the container on the block.

9. A container forming machine including a table having vertical channel walls terminating at the front edge of the table, a forming block pivotally mounted upon the table rearward of said front edge and extending forward and normally above and in line with the channel between said walls and in position clear of the table so as to permit a carton to be readily normally placed upon or removed from the end of the block, a clamping member beneath said block for clamping a blank against the under side of said block as the latter moves down toward the channel, means whereby the blank may be positioned between said block and channel while the former is in normal position, a plurality of hinged folding members at the forward end of the channel, means for causing said block to engage the blank and shape the same about said block by passing the latter into the channel between said walls, means responsive to said rocking means to swing said folding members on their hinges in succession to fold the blank to form the end of the container, means for restoring the block to its normal posi-

tion, a sliding sleeve on said block for pressing back flaps of the container and a carton manually superposed thereon after said block has been restored to its normal 5 position, and means for reciprocating said sleeve to perform said pressing operation.

10. A container forming machine including a table having a channel in its top opening upward, a rectangular forming block 10 normally at rest above said channel and movable into said channel and when in said channel having its end occupying a vertical plane transverse to said channel, a primary folding plate pivoted in the line of intersection of a second vertical plane with 15 the bottom of said channel, said second vertical plane being parallel and closely adjacent to said first mentioned plane, a secondary plate pivoted in the line of intersection 20 of said second plane with one side wall of said channel, and a third folding plate pivoted in the line of intersection of said second plane with the other side wall of said channel.

25. 11. In a container forming machine, a table having a channel therein, said channel being functionally integral with said table, and a plurality of folding plates located at the end of said channel and operative to 30 move from normal open positions to closed positions, said plates when in closed positions lying in a substantially vertical plane extending transversely of said channel.

35. 12. In a container forming machine, a table having a channel therein, a primary folding plate pivoted at the intersection of a transverse vertical plane and the bottom of said channel, a secondary folding plate pivoted at the intersection of said plane and one 40 side wall of said channel, and tertiary folding plate pivoted at the intersection of said plane and the other side wall of said channel.

45. 13. In a container forming machine, a plurality of folding plates operative in succession upon the folds of a blank; a common actuating head, crank arms and connecting rods between said head and plates, and yielding connections between said rods and head whereby the advance of said head causes successive actuations of said plates in a prescribed order.

55. 14. In a container forming machine, a plurality of independently pivoted folding plates adapted to operate in succession upon the folds of a blank, crank arms upon said plates respectively, an actuating head, connecting rods connected respectively at one end to said crank arms and at the other end passing through openings in said head, and 60 means cooperating with said rods and head to cause the actuation of the latter to actuate said folding plates in succession in a given order.

65. 15. In a container forming machine, a plurality of independently pivoted folding

plates adapted to operate in succession upon the folds of a blank, crank arms upon said plates respectively, an actuating head, connecting rods connecting respectively at one end to said crank arms and at the other end 70 passing through openings in said head, and coil springs upon said rods connected thereto respectively only at their ends nearest said plates and positioned so as to bring their free ends different distances from said head 75 in normal position, whereby the movement of said head from normal will engage said springs in succession and correspondingly operate the associated rods and folding plates. 80

16. A container forming machine including a table having a channel therein, said channel being functionally integral with said table, a pivoted forming block adapted to move into and out of said channel, folding plates for successive operation following the movement of said block into said channel, an actuating lever, a connection between said lever and block whereby said block moves into said channel upon the actuation 90 of said lever, and connections between said lever and folding plates whereby the latter are operated in succession immediately following said movement of the block. 95

17. A container forming machine including a table having a channel therein, a forming block pivoted to said table and having a rearwardly extending arm and a forwardly extending portion adapted to move into and out of said channel, a reciprocating sleeve 100 on said block toward its forward end, folding plates at the forward end of said channel for cooperation with said block, an actuating lever, a connection between said block and lever whereby the actuation of the latter causes the former to enter said channel, connections between said lever and folding plates whereby said plates are successively operated following the said entry of said block into said channel, and means for actuating said sleeve independently of said lever. 105

18. In a container forming machine, a forwardly protruding forming block upon which a container may be positioned, a sleeve 115 upon said block closely engaging the same and having forwardly and outwardly projecting yielding portions for engaging the container flaps to position them, said block having slots adjacent to said sleeve, an actuating lever, and a connection through said slots and the center of said block between said sleeve and lever whereby actuations of the lever produce reciprocations of the sleeve. 120

In testimony whereof, I hereunto subscribe my name this 26th day of March, A. D. 1924.
